UNITED STATES PATENT OFFICE.

LAMBERT B. RICHARDS, OF SHIELDS, PENNSYLVANIA, AND CHARLES P. WATKINS, OF LOUISVILLE, KENTUCKY, ASSIGNORS TO TATE-JONES & CO., INC., OF PITTSBURGH, PENNSYLVANIA, A CORPORATION OF PENNSYLVANIA.

FURNACE.

1,308,743.

Specification of Letters Patent.

Patented July 1, 1919.

Application filed October 7, 1918. Serial No. 257,141.

To all whom it may concern:

Be it known that we, LAMBERT B. RICHARDS and CHARLES P. WATKINS, citizens of the United States of America, residing at 5 Shields, Pa., and Louisville, Ky., respectively, have invented a new and useful Furnace, of which the following is a specification.

Our invention relates to furnaces of the 10 "over-fired" type employed for heat treating purposes.

One of the principal objects of the invention, is to enable the maintenance of a substantially even heat throughout the heat 15 treating chamber and particularly to provide for the heating of the lower portion of such chamber substantially to the same extent as the heating of the upper portion of the chamber.

20 Other objects of the invention are to secure the above mentioned results without injuriously affecting the contents of the heat treating chamber, and to accomplish all of the foregoing in a simple and practical way.

25 Briefly stated, the invention resides in the combination with an over-fired furnace, embodying upper and lower communicating combustion and heating chambers, and a burner supplying heat to the combustion chamber, of an auxiliary or supplementary burner, furnishing heat directly to the heating chamber at a point remote from that supplied by the main burner and independently regulatable to enable adjustment of 30 the supplementary heat to the extent needed.

35 Other features of the invention will appear as the specification proceeds and will be more readily understood from a consideration of the accompanying drawing, wherein 40 we have illustrated the invention embodied in one of its practical commercial forms.

In said drawing:

Figure 1 is a transverse sectional view of 45 an over-fired furnace having features of the invention incorporated therein.

Fig. 2 is a broken horizontal sectional view taken substantially on the plane of the line 2-2 of Fig. 1.

50 Fig. 3 is a fragmentary longitudinal sectional view of the furnace, taken substantially on the plane of the line 3-3 of Fig. 1.

Referring now to the drawing in detail, 5 designates the upper combustion chamber, and 6 the lower heat treating chamber, the

two chambers being in communication 55 through a perforated substantially horizontally disposed wall or arch 7 extending transversely across between the side walls of the furnace body.

The upper or combustion chamber is provided with burner openings 8 in the side walls thereof through which the burners 9 discharge. These burners may be "staggered" at opposite sides of the furnace as indicated in Fig. 1 as is customary in this 60 art.

The waste products escape from the heating chamber in the construction illustrated, through exhaust flues 10 extending from the bottom portion of the heating chamber up 70 along the side walls of the furnace, these exhaust flues also being staggered at opposite sides of the furnace as indicated in Fig. 1.

With the construction thus far described, 75 the heat generated in the combustion chamber descends through the perforated arch into the heat treating chamber, the waste products escaping as above indicated from the lower portion of said chamber. The 80 tendency of this construction is to provide a greater degree of heat in the upper portion of the heating chamber than in the lower portion thereof—in other words, there is ordinarily somewhat of a deficiency of 85 heat in the lower portion of said chamber. To overcome this deficiency, we have provided the supplemental or auxiliary burners 11 arranged to supply heat directly to the lower portion of the heat treating chamber. The 90

heat treating chamber is for this purpose provided with burner passages 12 in the opposite side walls thereof, preferably staggered as indicated in Fig. 1, these passages preferably being forked where they enter the heating chamber, as indicated at 13 in Figs. 2 and 3, to provide a baffle wall 14 for breaking up the blast from the burners. In addition to the baffling effect, this forked construction of the burner passages provides 100 additional length for enabling complete combustion of the gases before entering the heat treating chamber, and the burner passage may be further lengthened by extending the same on the downward incline, as indicated in Fig. 1. The forked exits of the burner passage may be disposed horizontally 105

as shown, and this, in combination with the

inclined entry of the passage provides a further baffling effect.

The supplemental burners 11 are preferably controllable by valves or other means, 5 such as indicated at 15 to enable their adjustment to a point where just enough additional heat will be supplied to the bottom portion of the chamber to compensate for the drop in temperature between the top 10 and bottom sections of such chamber. The main burners 9 are also usually provided with valves or controlling means such as indicated at 16 so that the two sets of burners are independently controllable to secure any 15 desired heating effects.

This invention is particularly desirable where the heat treating chamber is of considerable height, or where large articles are being treated, inasmuch as the lower portion 20 of the heat treating chamber may be brought up to the same temperature as the upper portion thereof, and the articles be thereby subjected to substantially the same degree of heat throughout. Injury to the 25 articles under treatment by oxidization or the like is prevented by providing for substantially complete combustion of the fuel of the supplementary burners before entering the heat treating chamber.

30 We claim:

1. In an over-fired furnace, the combination of an upper combustion chamber, a lower heating chamber, a perforated wall separating said chambers, a burner discharging 35 into the combustion chamber and furnishing heat to the upper part of the heating chamber through the perforated wall, and an independently controllable burner discharging into the lower portion of the 40 heating chamber and above the floor thereof

for providing the supplementary heat necessary to bring the lower part of the heating chamber to approximately the same temperature as the upper part of said chamber.

2. In an over-fired furnace, the combination of communicating combustion and heat treating chambers, said heat treating chamber being provided with a burner passage in the wall thereof having branches opening directly into said chamber, a burner discharging 45 into said passage, and an independently controllable burner discharging into the combustion chamber. 50

3. In an over-fired furnace, the combination of communicating combustion and heat 55 treating chambers, said heat treating chamber being provided with a burner passage in the wall thereof having branches opening directly into said chamber, and a wall between said branches providing a baffle, a 60 burner discharging into said passage against said baffle, and an independently controllable burner discharging into the combustion chamber.

4. In an over-fired furnace, an upper combustion chamber, a lower heating chamber, a perforated wall separating said chambers, a burner discharging 65 into the combustion chamber and furnishing heat to the upper portion of the heating chamber through the 70 perforated wall, said heating chamber having a downwardly inclined burner passage opening into the lower portion thereof, and an independently controlled burner discharging 75 into said downwardly inclined passage for independently supplying heat to the lower portion of the heating chamber.

LAMBERT B. RICHARDS.
CHARLES P. WATKINS.
